UNITED STATES PATENT OFFICE.

FRANK G. JOHNSON, OF KANKAKEE, ILLINOIS.

STRENGTH-TESTING DEVICE.

1,115,826.

Specification of Letters Patent.

Patented Nov. 3, 1914.

Application filed November 7, 1913. Serial No. 799,745.

To all whom it may concern:

Be it known that I, FRANK G. JOHNSON, a citizen of the United States, residing at Kankakee, in the county of Kankakee and 5 State of Illinois, have invented certain new and useful Improvements in Strength-Testing Devices, of which the following is a description, reference being had to the accompanying drawings, forming a part of this 10 specification, in which corresponding numerals of reference in the different figures indicate like parts.

The object of my invention is to provide a cheap, simple and effective strength-testing 15 device for the use of athletes and others in athletic exercise and especially for testing and indicating the strength of arms and fingers.

To these ends, my invention consists in the 20 combination of elements hereinafter more particularly described and definitely pointed out in the claims.

In the drawings, Figure 1 is a central vertical section viewed from one side, of an 25 apparatus embodying the features of my invention. Fig. 2 is a sectional view in plan taken upon the line 2—2, Fig. 1. Fig. 3 represents a section taken upon the line 3—3, Fig. 1, viewed in the direction of the arrows 30 there shown. Fig. 4 indicates a section taken upon the line 4—4, Fig. 3, viewed in the direction indicated by the arrows. Fig. 5 is a front elevation, partly in section, taken upon the line 5—5, Fig. 1. Fig. 6 is 35 a front view in detail of a portion of the upper part of the machine, the covering plate being removed to show a portion of the sliding actuating bar, and movable indicating block. Fig. 7 is a transverse sec- 40 tional view thereof, and Fig. 8 is a side view of the lower portion of the apparatus.

Referring to the drawings, 1, Figs. 1, 2, 3, 4 and 8, indicates a metal bracket adapted to be bolted or otherwise rigidly attached to 45 a wall, post or other vertical support, 2. Said bracket is provided with laterally ex- 50 tended tongues 3, 3, Figs. 2, 4 and 8, adapted to enter grooves in a casing or sliding mem- 55 ber 4, which is rigidly attached to the back 5, of the apparatus or machine proper. Said bracket is provided with a vertical slot 6, which is extended upwardly from near the lower portion to the top thereof for the reception of a clamping screw 7, which 55 is passed through a bore in the part 4, and adapted to be secured in any desired posi-

tion by means of a thumb-nut 8, for the purpose of adjusting the relative height of the main structure to accommodate it to the use of tall or short persons. When adjusted by 60 means of the mechanism about to be described, the parts may be rigidly clamped together by means of said thumb-nut.

The lower portion of the apparatus is pro- 65 vided with a casing having side-walls 9, through one of which is projected a shaft 10, having a gear 11, upon its inner end, adapted to engage a rack 12, formed upon the bracket 1. A ratchet-wheel 13 is rigidly attached to the shaft 10, upon the outside 70 of the casing, and is adapted to be locked in place by means of a pawl 14, held normally in an engaging position by a spring 15. A crank 16, Figs. 5 and 8, is rigidly attached to the shaft, upon turning which the casing 75 of the apparatus may be raised or lowered to the desired height.

Rigidly attached to the back 5, within the casing, is a bracket 17, to which is se- 80 cured a plurality of relatively long coiled springs 18, and in like manner, one or more shorter coiled springs 19. The upper ends of the springs 18 are attached to an elongated head or member 20, upon the forward end of an arm 21, the rear end of which is 85 provided with vertical flanges 22, which are rigidly attached to the lower end of a sliding bar 23, which is fitted to slide in a vertical groove 24, better shown in Figs. 6 and 7, formed in the back of the casing, said bar 90 being held in place by means of overlapping flanges or strips 25, 26, the latter of which is graduated to form an indicating scale as shown in Fig. 5, for the purpose hereinafter stated. The springs 19 have rods 27, Fig. 95 5, attached to the upper ends thereof and extended loosely through bores in the part 20. Said rods extend a predetermined dis- 100 tance above said part, and are provided with heads 28, also shown in Fig. 2, which are adapted to be engaged by the member 20 when the latter is raised a predetermined distance.

Attached to the part 20 is a lifting strap 29, which is extended upwardly through an 105 opening in a horizontal top member 30, forming a part of the main casing. Secured around and within said opening is a fitting 31, having friction rollers 32, between which the strap 29 is passed. The upper end of 110 said strap is attached to a bail 33, adapted to rest normally against the part 31, and

provided with a handle member 34. Links 35, serve to connect the handle 34 with a like handle 36, at a higher level, while similar but longer links 37 are connected with a handle 38.

5 A bracket 39 is jointedly attached to the front of the casing which serves as a support for a cushion 40, to serve as an elbow-rest for the user. The purpose in placing 10 the handles at different heights is to provide for a partial or full arm exercise.

15 The sliding bar 23, is intended to operate an indicator which preferably consists of a sliding block 41, Figs. 1, 5, 6 and 7, which 20 is loosely fitted within the groove 24 and adapted to be held at any height to which it may be moved by means of springs 42. A stud 43, extending outwardly through a slot as shown and provided with a knob at its outer end for returning it to a normal position when lifted by the bar 23, serves as a support for an indicating finger 44.

25 In operating the device, the user grasps one of the handles and lifts it to whatever height he may be able. This action results in raising the bar 29, and in turn, the indicator block 41. It is desirable however that some means should be provided for preventing a sudden recoil of the springs, and enabling the parts to be returned to a normal 30 position, without shock. This I prefer to accomplish as follows: Journaled in suitable bearings in the casing is a shaft 45, having an operating crank 46. A ratchet-wheel 47 is rigidly attached to said shaft, and adapted to be held against reversal by means of a spring pressed pawl 48. A drum 49 is rigidly secured to the shaft 45, to one portion of which is attached one end of a take-up 40 strap 50, the other end of which is attached to the part 20, in the same manner as is the strap 29. A take-up weight 51 is also suspended from the drum 49 by means of a cord 52, one end of which is attached to the 45 periphery of the drum. The gravity of said weight is just sufficient to overcome the friction of the parts, and cause the shaft 45 to be rotated when the springs 18 and 19 are expanded by an upward pull upon the 50 strap 29, so that a recoil of the springs will be prevented by the action of the take-up strap 50 and the connecting parts which are controlled by the action of the ratchet-wheel 47 and pawl 48.

55 An upward lift upon either of the handles chosen, serves first to expand the springs 18. When the part 20 is raised into contact with the beads 28, the springs 19 are brought into 60 action, and an additional resistance imposed. This feature is intended to meet the requirements of persons of exceptional strength. As the part 20 is lifted, the bar 23 is raised, thereby moving the indicator block 41 to a corresponding height upon the 65 scale. When the operator releases the handle,

the bar is still held in place by the take-up mechanism, whereupon an attendant grasps the handle 46, throws the pawl 48 out of engagement, and lowers the indicator bar by means of the crank. The indicator block, 70 however, remains in place, and may be restored at will to its normal position by means of the knob thereon.

The reason why I prefer to use a plurality of springs is that it enables me to utilize 75 wire of smaller gage and therefore shorter coils. This enables the full movement desired, preferably about sixteen inches, to be accomplished which would not be practical in the simple way shown, and in the space 80 available, were wire of large gage to be employed.

It is desirable that the device should be secured against unwarranted manipulation. This may be accomplished by means of any 85 suitable lock adapted to prevent an upward movement of the bar 23. For example, in Fig. 5, I have shown a dog 53, pivoted at 54, to the back of the casing. A detent 55 is adapted to engage a notch 56, in the bar 90 23, while the movement of the lower end of said dog is adapted to be controlled by means of a screw 57, tapped into a nut 58, which is swiveled in said lower end. The longitudinal movement of said screw is prevented by the head 59, and a washer 60, located upon opposite sides of the wall 9.

Having thus described my invention, I claim:

1. A machine of the character described, 100 comprising a handle in connection with means offering a yielding resistance to the movement thereof, said means comprising primary and secondary yielding resistance means, the latter being normally inert, means 105 for bringing said secondary resistance means into action at a predetermined period in the movement of the handle, take-up means arranged to move in harmony with the yielding of said resistance means when force is 110 applied to said handle, means for preventing a reverse movement of said take-up means, an indicator scale and an indicator arranged to indicate thereon the force applied to said handle. 115

2. A machine of the character described, comprising a handle in connection with means for offering a yielding resistance to the movement of said handle, said means comprising primary and secondary resistance 120 springs, said primary springs being arranged to resist the movement of said handle throughout the extent of its travel in one direction, means for bringing said secondary springs into action at a predetermined period in said travel, take-up means for arbitrarily holding said springs against reversal, and indicating means for indicating the relative movement of said handle. 125

3. A testing machine for testing the 130

strength of the arm muscles, comprising a handle, means connected therewith for offering a yielding resistance to the movement thereof, take-up means arranged to move in 5 harmony with the movement of said handle when force is applied thereto, means for preventing a reverse movement of said take-up means, an indicator scale, an indicator arranged to indicate thereon the degree of 10 force applied to said handle, a casing for said mechanism, a stationary supporting member for said casing, and means interposed between said casing and said supporting member for adjusting said machine to 15 adapt it to the use of persons of varying height.

4. A machine of the character specified, comprising a handle, yielding resisting means, flexible means for connecting said handle to said resisting means, a shaft having a drum rigidly mounted thereon, flexible means for connecting said resisting means to the periphery of said drum, means for actuating said drum to act as a take-up when 20 said handle is moved in a given direction, a ratchet-wheel rigidly connected with said shaft, a pawl for engaging the same, and means for indicating the relative movement of said handle to indicate the degree of force 25 applied thereto.

5. A machine of the character described, comprising a handle, yielding resisting means, flexible means for connecting said handle to said resisting means, a shaft having a drum rigidly mounted thereon, flexible means for connecting said resisting means to the periphery of said drum, means for rotat- 30

ing said drum to act as a take-up when force is applied to said handle to move it in opposition to said resisting means, a ratchet and 40 pawl for locking said drum against reverse movement, a vertically slidable bar arranged to be moved when force is applied to said handle, an indicator adapted to be actuated by said bar and an indicating scale in oper- 45 ative proximity to said indicator.

6. A machine of the character described, comprising a handle, yielding resisting means, flexible means for connecting said handle to said resisting means, a shaft having a drum rigidly mounted thereon, flexible means for connecting said resisting means to the periphery of said drum, means for rotating said drum to act as a take-up when force is applied to said handle to move it in 50 opposition to said resisting means, a ratchet, and pawl for locking said drum against reverse movement, a crank upon said shaft, a vertically slidable bar arranged to be moved when force is applied to said handle, a detached movable indicator adapted to be moved by said bar, frictional means for holding said indicator in a given position when the bar is reversed, and a scale in operative proximity to said indicator. 55

In testimony whereof, I have signed this specification in the presence of two subscribing witnesses, this first day of November 1913.

FRANK G. JOHNSON.
